FOUNTAIN PEN

Joseph White, Comstock, N. Y.

Application February 29, 1936, Serial No. 66,465

6 Claims. (Cl. 120—42)

The present invention relates to improvements in fountain pens.

The primary object of the invention is to provide a pen that will contain ink of several different colors and present novel valve means for selecting the desired color of ink to be used.

A further object of the invention is the construction and arrangement of a rotatable disc and valve closely associated with the discharge ends of the ink-carrying reservoirs and pen point, whereby when one color of ink is selected for use the other color will be forced back into its reservoir, thus alleviating any possibility of the ink becoming mixed.

The invention will be fully and comprehensively understood from a consideration of the following detailed description when read in connection with the accompanying drawing which forms part of the application.

In the drawing:

Fig. 1 is a transverse sectional view of the new and improved pen and illustrating in plan the ink carrying reservoirs.

Fig. 2 is a sectional view taken on line 2—2 of Fig. 1.

Fig. 3 is a perspective view of the parts forming the valve means for selecting and controlling the desired color of ink to be used.

Fig. 4 is a sectional view taken on line 4—4 of Fig. 1; and

Fig. 5 is a diagrammatic view illustrating the movement of the eccentrically mounted valve with respect to the discharge opening.

Referring to Fig. 1 of the drawing, it will be noted that the invention comprises a barrel 6 provided with a partition 7 for dividing the barrel into two sections for receiving the collapsible ink reservoirs 8 and 9. For purposes of illustration, the invention has been disclosed in use with two reservoirs, but it is to be understood that any desired number can be effectively used without departing from the spirit of the invention.

Each of the reservoirs may be supplied with ink thru the use of the usual filling means including the pivoted arm 10 engaging with the longitudinal compressing member 11. When replenishing the supply of ink in each reservoir it will of course be necessary to control the valve selecting means to be later described.

Mounted within the barrel 6 and adjacent the discharge end of the collapsible reservoirs 8 and 9, is a plug member 12. The ends of said reservoirs engage upstanding shoulder portions 13 of the plug member 12 and the ink is fed to the pen thru the channels 14 and 15 from the reservoirs

8 and 9, respectively, the said channels being formed within the body of the plug member 12.

Positioned adjacent the plug member 12 is the feeding head 16 constructed with a recess 17 and supporting feed troughs 18 and 19 directly connected to the channels 14 and 15 of the reservoirs 8 and 9, respectively. The feed troughs 18 and 19 are supported from shoulder portions depending from the plug member 12 and upstanding shoulder portions forming a part of the feeding head.

Centrally disposed within the feeding head 16 and directly connected to said troughs 18 and 19 is the member 20 which aids in supporting the pen point 21 and thru which the supply of ink is fed to said pen point. A pair of channels 22 and 23 have communication with the feed troughs 18 and 19 and are controlled by the means illustrated in Fig. 3 of the drawing. The valve controlling means comprises the rotatable disc 24 provided with recesses 25 and 26 adapted to be aligned with the feed troughs 18 and 19, respectively, depending upon the desired color of ink to be used. The disc 24 is rotatably mounted within the body portion of the member 20 and is positioned in close proximity to the discharge ends of the feed troughs 18 and 19, as illustrated in Fig. 1 of the drawing. Means for controlling the rotation of the disc 24 includes the transversely disposed rod 27 secured within the upstanding portion 28 of the valve disc 24. The rod 27 extends transversely thru the barrel of the pen and has its opposite end passing thru the end of the barrel and connected to a knurled nut 29 for controlling the rotation thereof.

The other portion of the valve controlling means comprises the cone-shaped valve 30 connected to the disc 24 thru the medium of the connecting rod 31, the upper end of which is secured within a recess in the bottom portion of the valve disc 24 so that said disc 24 and cone valve 30 will rotate in unison.

Diagonally disposed and at diametrically opposite points within the cone-shaped valve 30 are a pair of channels 32 and 33 adapted to align with the openings 25 and 26, respectively, of the valve disc 24 for controlling the selected color of ink to be fed to the pen point 21. It is to be understood that the valve disc 24 and valve 30 will rotate in unison upon turning of the knurled nut 29 so that ink will flow from a selected reservoir thru its respective channel into the feeding head 16 and thence thru either channel 22 or 23 to the pen point 21.

Integral with the body portion of the valve 30

and eccentrically disposed relative thereto is the controlling member 34 which rotates within the recess 35 of the member 20. The member 34 is so mounted that upon rotation of the valve 5 means, ink will be supplied to the pen and the ink of the opposite color will be forced back into its reservoir so as to prevent a mixing of the several colored inks. This can readily be determined by referring to Figs. 1 and 5 of the drawing. In Fig. 10 1 the respective channels are open so that a supply of ink will be fed to the pen point 21 from the ink supplying reservoir 9. During the rotation of the rod 27 and its supporting valve disc 24 and cone 30 to select an ink, the ink which normally would remain in the channel 35 that has been fed from the reservoir 8 will be forced backwardly and up into the channel 22. It is to be understood that this action will occur when the various parts are rotated so that the member 34 15 has assumed the position illustrated in Fig. 1. The converse is true if it is desired to supply ink from the reservoir 8. The action of the member 34 can be determined by an inspection of the illustration in Fig. 5 of the drawing. The center 20 of rotation of the disc 24 and valve 30 is indicated by the letter A and the angle of rotation is confined by the radial lines projecting from the point A. Due to the eccentricity of the member 34 the center of same will be caused to swing 25 from the point B to the point C, thereby moving the opposite side of said member into contact with the opposite wall of the recess 35 in which it is contained, thus causing the ink therein to be squeezed out.

30 The feeding head 16 is provided with the usual longitudinal thread portion 36 for attaching the cap 37 for protecting the pen when not in use. It is believed that the operation of the device is clearly evident from the above description. In 35 use, different colored inks, for example, red and black, may be contained within the reservoirs 8 and 9, respectively. When it is desired to use the pen for writing with black ink the knurled portion 29 is engaged by the fingers and rotated a degree sufficient to provide a continuous discharge channel from the reservoir 9 thru the channels 15, 19 and 23, respectively. Rotation of the knurled portion 29 will cause the valve disc 24 and valve 30 to rotate so as to align their 40 respective openings 26 and 33 with the feed channel 19. If the pen had previously been used for writing with red ink, the residue in the channel 35 will be squeezed or forced back into the channel 22, thus preventing a mixing of the inks.

45 It is to be understood that this improvement is capable of extended application and is not confined to the exact showing of the drawing nor to the precise construction described and, therefore, such changes and modifications may be 50 made therein as do not affect the spirit of the invention nor exceed the scope thereof as expressed in the appended claims.

55 What is claimed as new is:

1. A fountain pen comprising a barrel, ink carrying reservoirs supported within said barrel, a feeding head, a pen point supported by said feeding head, means for selecting and controlling an ink to be fed from said reservoir to said pen point, said means comprising a disc having 60 discharge parts rotatably mounted within said feeding head, a cone-shaped valve rotatable with and spaced from said disc and having grooves adapted to align with the discharge parts in said disc, an eccentric member depending from and 65 integral with said cone-shaped valve and means

within said barrel for rotating said disc and valve.

2. A fountain pen comprising a barrel, ink carrying reservoirs supported within said barrel, a feeding head, ink guide means supported between said reservoirs and feeding head, a pen point supported by said feeding head, means for selecting and controlling an ink to be fed from said reservoirs to said pen point, said means comprising a disc having discharge ports mounted 10 therein, a cone-shaped valve rotatable with and spaced from said disc and having grooves adapted to align with the discharge ports in said disc, and means depending from said cone-shaped valve for regulating the supply of ink within the 15 feeding head.

3. A fountain pen of the type described comprising a barrel, a plurality of collapsible fluid carrying reservoirs, a plug positioned within said barrel adapted to support said reservoirs and having passages formed therein communicating with the interior of the reservoirs, a feeding head having a plurality of passages extending at least partially therethrough mounted on said barrel, fluid guide means communicating with said passages 20 and, through the passages in said plug with the reservoirs, means for regulating the flow of fluid in the passages within the feeder head comprising a rotary valve mounted within said head having openings formed therein alignable with each 25 of said passages but with only one passage at a time, a guide member substantially conical in shape having cutaway portions formed in the peripheral part thereof registerable with the outlet portion of the fluid passages formed in the 30 head whereby fluid can be guided from the reservoirs through the plug, valve and along the conical member to the apex thereof, a chamber formed in said feeder head and communicating with the apex of said conical member, and a pen 35 point supported on said head communicating with said chamber.

4. A fountain pen of the type described comprising a barrel, a plurality of collapsible fluid carrying reservoirs, a plug positioned within said barrel adapted to support said reservoirs and having passages formed therein communicating with the interior of the reservoirs, a feeding head having a plurality of passages extending at least partially therethrough mounted on said barrel, fluid guide means communicating with said passages and, through the passages in said plug with the reservoirs, means for regulating the flow of fluid in the passages within the feeder head comprising a rotary valve mounted within said head having openings formed therein alignable with each of said passages but with only one passage at a time, a guide member substantially conical in shape having cutaway portions formed in the peripheral part thereof registerable with the outlet portion of the fluid passages formed in the head whereby fluid can be guided from the reservoirs through the plug, valve and along the conical member to the apex thereof, said conical member being rotated simultaneously with the valve 45 and associated therewith, a chamber formed in said feeder head and communicating with the apex of said conical member, and a pen point supported on said head communicating with said chamber.

5. A fountain pen of the type described comprising a barrel, a plurality of collapsible fluid carrying reservoirs, a plug positioned within said barrel adapted to support said reservoirs and having passages formed therein communicating 50

with the interior of the reservoirs, a feeding head having a plurality of passages extending at least partially therethrough mounted on said barrel, fluid guide means communicating with said passages and, through the passages in said plug with the reservoirs, means for regulating the flow of fluid in the passages within the feeder head comprising a rotary valve mounted within said head having openings formed therein alignable with each of said passages but with only one passage at a time, a guide member substantially conical in shape having cutaway portions formed in the peripheral part thereof registerable with the outlet portion of the fluid passages formed in the head whereby fluid can be guided from the reservoirs through the plug, valve and along the conical member to the apex thereof, said conical member being rotated simultaneously with the valve and associated therewith, a chamber formed in said feeder head and communicating with the apex of said conical member, means for at least largely preventing intermixing of fluids from different reservoirs in said chamber, and a pen point supported on said head communicating with said chamber.

6. A fountain pen of the type described comprising a barrel, a plurality of collapsible fluid carrying reservoirs, a plug positioned within said barrel adapted to support said reservoirs and having passages formed therein communicating with the interior of the reservoirs, a feeding head

having a plurality of passages extending at least partially therethrough mounted on said barrel, fluid guide means communicating with said passages and, through the passages in said plug with the reservoirs, means for regulating the flow of fluid in the passages within the feeder head comprising a rotary valve mounted within said head having openings formed therein alignable with each of said passages but with only one passage at a time, a guide member substantially conical in shape having cutaway portions formed in the peripheral part thereof registerable with the outlet portion of the fluid passages formed in the head whereby fluid can be guided from the reservoirs through the plug, valve and along the conical member to the apex thereof, said conical member being rotated simultaneously with the valve and associated therewith, a chamber formed in said feeder head and communicating with the apex of said conical member, means for at least largely preventing intermixing of fluids from different reservoirs in said chamber, comprising a vane-like member eccentrically mounted on the apex of said conical member and cooperating with the walls of said chamber whereby as the valve is rotated to change the source of fluid supply, the residual fluid in the chamber will be at least largely displaced before the different fluid enters, and a pen point supported on said head communicating with said chamber.
